WIRE MANIPULATING TOOL

Samuel S. Colt, Orange, N. J.

Application September 21, 1936, Serial No. 101,723

6 Claims. (Cl. 140—118)

This invention relates, generally, to an improved tool for manipulating wire; and the invention has reference, more particularly, to a novel tool for twisting and tightening wire ties. 5 This application is a continuation in part of my prior application for United States Letters Patent Ser. No. 96,641, filed on or about August 18th, 1936.

This invention has for its principal object to 10 provide a novel tool for engaging and twisting together the end portions of wire ties, whereby such ties are tautly drawn about or in assembled connection with bodies or parts to be bound thereby. The novel tool, adapted to so function, 15 may be usefully employed for many purposes, but is especially useful as a means for tightening and securing wire ties employed in assembling parts of concrete pouring forms, in assembling parts of building structures, and in various similar fields. 20

The invention has for a further object to provide a novel tool for the purposes described, comprising in combination a lever bar having means to receive and engage wire ends to apply twisting motion thereto when the lever bar is turned 25 about its center, and a locking bar rotatably related to said lever bar, having means cooperative with the latter to dispose and grip the wire ends against slip when the wire is subjected to twisting movement; said lever bar having a centrally disposed adjustable and retractable core element coincident to the axis of rotation of the 30 tool, this core element being in threaded connection with said lever bar, and having, for projection from the work opposing face of the latter a tapered wire twist support. 35

Other objects of this invention, not at this time more particularly enumerated, will be clearly understood from the following detailed description of the same. 40

An illustrative embodiment of this invention is shown in the accompanying drawings, in which:—

Fig. 1 is a top plan view of the tool of this invention; Fig. 2 is a bottom plan view of the same; and Fig. 3 is a longitudinal sectional view of the same. 45

Fig. 4 is a front elevation showing the initial application of the tool of this invention to the ends of tie-wires of a concrete pouring form preparatory to engaging and twisting said wires; Fig. 5 is a vertical section taken on line 5—5 in Fig. 4, the tool being shown in side elevation. 50

Fig. 6 is a front elevation showing the tool operatively engaged with the tie-wire ends and in 55

the act of twisting the same together; and Fig. 7 is a vertical section, taken on line 7—7, the tool being shown in side elevation.

Fig. 8 is a longitudinal sectional view of the tool as applied to the tie-wire ends and in the act 5 of initially twisting the latter to tautened condition while the twists are supported by the operatively advanced tapered wire twist support of the core element; and Fig. 9 is a similar view 10 showing the tapered wire twist support of the core element retracted to permit of final operation of the tool to tighten the wire twists together, after the wire is fully drawn taut, so as to lock the wire against relaxation from its binding relation to the form structure; these latter 15 views are drawn on an enlarged scale.

Fig. 10 is a face view of a metallic bearing plate, suitable for attachment to a form structure bat- 20 ten, and adapted to provide a bearing for the tie, especially when said tie comprises extra heavy wire, soft iron rods or like heavy tie material.

Similar characters of reference are employed in the above described views, to indicate corresponding parts. 25

Referring to said drawings, the reference character 10 indicates a lever-bar having oppositely and longitudinally extending handles 11. Secured to the central portion of said lever-bar to project laterally outward therefrom is a hub-sleeve 12. Said hub-sleeve is provided with an internally threaded bore 13. Said lever bar is preferably provided, on one face thereof, with longitudinally disposed ribs 14, the same being laterally spaced to provide a seat for a die-member 15. Said die-member 15 has a central opening 16, whereby the same may be engaged over said hub-sleeve 12. Said die-member 15 is further provided with longitudinally spaced die-openings 17, respectively on opposite sides of said central opening 16. Said lever-bar is provided with openings 18 corresponding to and with which said die-openings 17 register. The die-member 15 is preferably made of hardened steel. 30 35 40

While it is preferred to employ the separable die-member 15, it is nevertheless not essential so to do, particularly in smaller sizes and cheaper grades of the tool, since, in the latter case, the openings 18 of the lever-bar may be suitably sized to serve as die-openings, and the die-member 15 may be omitted. The construction so modified is deemed to be and intended to be within the scope of the instant invention. 45 50

Rotatably mounted on said hub-sleeve 12 of lever-bar 10 is a locking bar 19 also provided with 55

oppositely and longitudinally extending handles 28. Preferably said locking bar 19 is spaced outwardly away from said lever-bar 10 by a hub portion 21. The outer or free end portion of said hub-sleeve 12 is screw-threaded to receive a keeper nut 22 to retain said locking bar and lever-bar in mutually cooperative assembled relation. Provided in one side margin of said locking bar 19, radially disposed from the common axis of rotation of said locking bar and lever bar at a distance substantially equivalent to the distance of one die-opening 17 from such axis of rotation, is a shoulder 23. A similar shoulder 24 is provided in the opposite margin of said locking bar 19, the same being similarly disposed relative to the other or opposite die-opening 17 of said lever-bar. Secured to the locking-bar to project from the under or inner side thereof, and respectively adjacent to the respective shoulders 23 and 24, are abutment pins 25. Said locking bar is further provided at each side thereof, and longitudinally spaced from the respective shoulders 23 and 24, with laterally projecting outwardly off-set bender hooks 26, the internal bights 27 of which are adapted, on reverse rotation of said locking bar relative to said lever bar, to engage and straighten out wire ends when it is desired to remove the tool therefrom, as will later appear.

30 Threaded through the internally threaded bore 13 of the hub-sleeve 12, for longitudinal adjustment, is the externally threaded body of a core element 28. Said core element is provided at its inner end for projection from the work opposing face of said lever-bar 10, with a tapered wire twist support 29. Connected with the outer end of said core element 28 is a suitable hand engageable means by which the core element may be turned to screw the same forward or backward 40 through the hub-sleeve 12. Illustrative of one suitable form of such means is the transverse lever bar 30 which is mounted through the outer end portion of said core element 28.

Illustrative of one use of the novel wire manipulating tool of this invention, I have shown, in Figs. 4 to 7 inclusive of the drawings, the application of the tool to U-shaped wire ties W employed to bind together the frame or batten members 31 and sides 32 of a concrete pouring form. 45 In such case the frame or batten members 31 are disposed against exterior faces of the form sides 32, the latter being spaced apart by intermediate spacer or spreader struts 33. The wire tie W is disposed to embrace one frame or batten member, extending therefrom through the sides and interior of the form, with the ends thereof engaged about the other frame or batten member.

To operatively apply the tool to the wire tie end portions W', the core element 28 is advanced 50 through the bore 13 of the hub-sleeve 12, to thereby project the tapered wire twist support 29 from the work opposing face of the tool. With the locking lever 10 swung or turned to an angular position whereby the die-openings 17 are exposed, the wire tie end portions W' are respectively entered through the respective die-openings 17 to extend therethrough, as shown in Figs. 4 and 5. When the tool has been thus initially applied to the wire tie end portions W', the locking bar 19 is turned (in the direction of the arrow in Fig. 4), thereby carrying the shoulders 23 and 24 respectively into engagement with the projecting wire tie end portions (as is shown in Figs. 4 and 5). The turning of the locking bar 19 is thereupon continued until the same is brought

into longitudinal alignment with the lever bar 10. This continued movement of the locking bar 19 relative to the lever bar 10, acts upon the projecting wire tie end portions W', through the engaging shoulders 23 and 24, to bend over said 5 wire ends exteriorly of the die-openings 17 and into abutment with the abutment pins 25, thereby gripping or snubbing the wire ends against lengthwise slip relative to the die openings 17.

Upon accomplishment of the above described 10 operations, the user grasps the parallel handle portions of both bars 10 and 19, and turns the entire tool about the central axis thereof and in the direction of the arrow shown in Fig. 6. The effect of this movement is to produce a twisting 15 movement of the wire tie end portions about the tapered wire twist support 29 of core element 28, thereby both drawing tight the stretches of wire extending around the frame or batten members and through the form, to bind the form sides and 20 spacers tightly together in assembled relation, while also starting the intertwisting of the ends of the wire tie together. The advantages of using the support 29 is that it provides a bend guiding means and support about which the 25 twisted convolutions of the wire tie ends may form, thus eliminating risk of kinking the wire with resultant likelihood of breakage thereof, and consequently permitting the wire tie to be drawn to maximum tautness quickly, safely and 30 efficiently (see Fig. 8).

After the wire tie end portions W' have been twisted together with their intertwined convolutions formed upon and supported by the tapered support 29, in the manner above described, the 35 operator thereupon backs out the core element 28 through the hub-sleeve 12 to thereby withdraw the tapered support 29 from the formed and intertwined wire end convolutions, whereupon by again turning the tool in clockwise direction 40 the inner intertwined wire end convolutions are tightened together and firmly and mutually interlocked against any relaxation from their tautened form structure tying relation (see Fig. 9).

When the wire tie ends have been interlocked 45 as stated, the tool is released from the wire extremities and removed. This is done by turning the locking lever 19 relative to the lever bar 10 in anti-clockwise direction, i. e. in direction opposite to that of the arrow in Fig. 4. Such movement 50 of the locking lever carries the bender hooks 26 into engagement with the bent over end portions W' of the wire with lifting effect thereon, so that the same are up-bent back to normal substantially straight outward extension from the die- 55 openings 17, whereupon the tool may be drawn outwardly and away from the wire ends and thus removed from the finished work.

The tool of this invention is capable of manipulating extra heavy wire and even ties of soft iron 60 rod material. When using such heavy tie material it is desirable to provide the batten members 31 of the form structure with protective bearing plate means over which the ends thereof may be drawn. A bearing plate means suitable for such 65 purpose is shown in Fig. 10, and comprises a metallic plate-like body 34, preferably somewhat longer than the width of the batten upon which it is to be applied. This body 34 may be secured across the face of the batten, as by driving nails 70 through perforations 35 provided for the purpose. When so arranged the ends of said body project beyond the upper and lower sides of the batten; these ends being provided with suitably shaped notches 36 to engage the tie wire or rod end por- 75

tions at points where the latter are drawn and bent over the corners of the batten. Said bearing plate prevents undue crushing or mutilation of the battens, when the wires or rods are tautened and secured.

I am aware that changes could be made in the above described tool structure, and that many apparently widely different embodiments of this invention could be made without departing from 10 the scope thereof. It is therefore intended that all matter contained in the above description or shown in the accompanying drawings shall be interpreted as illustrative and not in a limiting sense.

15 I claim:—

1. A tool of the kind described, comprising a lever bar having spaced openings for the extension therethrough of wire end portions desired to be twisted together, a locking bar rotatably 20 connected with said lever bar, said locking bar having means to engage and bend projecting parts of said wire end portions against withdrawal from said lever bar openings, a wire twist supporting means carried by the tool and aligned 25 with the axis of rotation thereof, and means to advance and retract said supporting means.

2. A tool of the kind described, comprising a lever bar having spaced openings for the extension therethrough of wire end portions desired 30 to be twisted together, a locking bar rotatably connected with said lever bar, said locking bar having means to engage and bend projecting parts of said wire end portions against withdrawal from said lever bar openings, a core element 35 aligned with the axis of rotation of the tool, said core element being adjustably movable along said axis, and a wire twist supporting means extending from the inner end of said core element and adapted to be advanced or retracted 40 by manipulation of the latter.

3. A tool of the kind described, comprising a lever bar having a central hub portion provided with an internally screw-threaded bore, said lever bar having openings respectively spaced therein 45 on opposite sides of said hub portion for the extension therethrough of wire end portions desired to be twisted together, a locking bar rotatably mounted on said hub portion over said lever bar, said locking bar having means to engage and bend projecting parts of said wire end portions against withdrawal from said lever bar openings, a core element threaded through said hub bore having a tapered wire twist supporting means 50 adapted to be projected or retracted from the

work opposing face of the tool by manipulation of said core element.

4. A tool of the kind described, comprising a lever bar having a central hub portion provided with an internally screw-threaded bore, said lever bar having openings respectively spaced therein on opposite sides of said hub portion for the extension therethrough of wire end portions desired to be twisted together, a locking bar rotatably mounted on said hub portion over said lever bar, 10 said locking bar having means to bend over projecting parts of said wire end portions when said locking bar is turned in one direction relative to said lever bar, said locking bar also having additional means to engage and bend back to initial 15 position said bent wire end portions when said locking bar is turned in the opposite direction relative to said lever bar, a core element threaded through said hub bore having a tapered wire twist supporting means adapted to be projected or retracted from the work opposing face of the tool 20 by manipulation of said core element.

5. A tool of the kind described, comprising a lever bar having spaced openings for the extension therethrough of wire end portions desired 25 to be twisted together, a locking bar having means to bend over projecting parts of said wire end portions when said locking bar is turned in one direction relative to said lever bar, said locking bar also having additional means to engage 30 and bend back to initial position said bent wire end portions when said locking bar is turned in the opposite direction relative to said lever bar, a wire twist supporting means carried by the tool 35 and aligned with the axis of rotation thereof, and means to advance and retract said supporting means.

6. A tool of the kind described, comprising a lever bar having spaced openings for the extension therethrough of wire end portions desired 40 to be twisted together, a locking bar having means to bend over projecting parts of said wire end portions when said locking bar is turned in one direction relative to said lever bar, said locking bar also having additional means to engage 45 and bend back to initial position said bent wire end portions when said locking bar is turned in the opposite direction relative to said lever bar, a core element aligned with the axis of rotation 50 of the tool, said core element being adjustably movable along said axis, and a wire twist supporting means extending from the inner end of said core element and adapted to be advanced or retracted by manipulation of the latter.

SAMUEL S. COLT.
